UNITED STATES PATENT OFFICE.

DAVID M. ROSENTHAL, OF SOUTHBRIDGE, MASSACHUSETTS.

FURNITURE.

1,412,895.

Specification of Letters Patent. Patented Apr. 18, 1922.

Application filed October 1, 1920. Serial No. 413,987.

To all whom it may concern:

Be it known that I, DAVID M. ROSENTHAL, a citizen of the United States, residing at Southbridge, in the county of Worcester and 5 State of Massachusetts, have invented certain new and useful Improvements in Furniture, of which the following is a specification.

This invention relates to improvements in 10 furniture and has particular reference to a novel and improved construction which may be interchangeably employed in a variety of different positions or relationships as may be desired.

15 One of the principal objects of the present invention is the provision of a combination cabinet or similar article of furniture which while particularly adapted for use in the equipment of clothing or similar stores is 20 also adapted for use within the home and which is so constructed with interlocking and interchangeable parts as to be capable of ready adaptation to the requirements of the particular configuration of the portion 25 of the room in which it is to be located.

A further and important advantage of the 30 present invention is the provision of an article of this character adapted to be manufactured and sold as independent units or sections each complete in itself but adapted to interlock and combine with other corresponding units to the end that if desired an entire store or the like can be completely 35 fitted up with the necessary containers, display racks and cases for the entire assortment of goods, complete with dressing rooms, mirrors, wall, semi-partition cabinets, etc., properly fitting any given wall 40 space without the necessity of having said fixtures specially built for a particular location or permanently affixed to the building.

Another purpose of the present invention is the provision of store furniture or fittings which can be shifted as desired to alter the 45 interior appearance of the shop without expense, which may be employed to quickly and desirably fit up a store without special carpenter work or interference with the regular interior finish of the building, and 50 which can be easily removed without damage and will be in perfect shape and perfectly adapted for use in a new location.

Other objects and advantages of my improved construction should be readily apparent by reference to the following specification taken in connection with the accom-

panying drawings, and it will be understood that I may make any modifications in the specific details of the construction shown and described within the scope of the appended 60 claims without departing from or exceeding the spirit of my invention.

Figure I represents a perspective view of a unit embodying my invention.

Figure II represents a plan view thereof. 65

Figure III represents a plan view showing another arrangement of the parts.

Figure IV represents a similar view of an arrangement to fit around a column or the like. 70

Figure V is a fragmentary view of a wall case with separating partition projecting therefrom.

Figure VI represents another fragmentary 75 plan view with parts broken away illustrating the arrangement to produce a small dressing room.

Figure VII represents a sectional view through the connecting means as on the line VII—VII of Figure II. 80

Figure VIII represents a bottom plan view illustrating the adjustable mirror support and locking devices.

Figure IX is a fragmentary plan view 85 of the mirror connection.

Figure X is a front view illustrating the mirror lock and,

Figure XI is a detail of the end door adjustment.

In the drawings, in which similar characters of reference are employed to denote corresponding parts throughout the several views, the numeral 1 designates the top of one of my improved cabinets or pieces of furniture, each piece or unit comprising two 90 similar but oppositely disposed top sections or outlines each of which is in the form of a rectangle diagonally cut at one end.

The purpose of this diagonal severing of the opposed ends of the sections should be 100 readily apparent by reference to the several figures of the drawings from which it will be seen that on account of this shape it is possible to arrange the two halves forming the unit either aligned with each other as indicated in Figures I and II, at right angles to each other as shown in Figure III to fit into a corner, reversely disposed at right angles as when it is desired to fit the sections around an angle in the wall, a 105 column in the middle of the room or the like, or the sections can be disposed in inter-

locking relation, one set back to back and the other straight and receiving the point of the doubled section as shown in Figure V. Furthermore, if preferred the sections 5 of the unit may be separated a sufficient distance to provide a small dressing room such as shown in Figure VI. These views thus 10 illustrate some of the possibilities of arrangement of my improved units and it should be understood that with an equipment of such units practically any size or shape of store can be quickly fitted up, saving both the time and expense of having suitable fittings specially built for the particular location.

In the construction of my sections, they are formed with the base portion 2 having rising therefrom the ends 3, back portions 4 and the diagonal end members 5 which 20 are ordinarily of panel construction but which if preferred may be made in the form of swinging doors 6 provided with the mirrors 7, usable either for exposed end portions, for sides of the dressing room or as 25 a double mirror corner affording a break in the line of the sections as indicated in Figure XI.

In the ordinary manufacture of my invention I provide as a part of the units a 30 mirror member comprising a frame 8 and the reflecting glass portion 9. This mirror is of such size as to be interchangeably employed in connection with the sections of the unit according to the particular arrangement desired. Its width is such that it 35 will just fill in the space between the fronts of the two halves of the unit when the same is straight along the wall, will serve to cover the ends of the doubled unit when 40 it is disposed in partition arrangement as shown in Figure V, will serve as the back for the dressing room when the sections are separated as shown in Figure VI, or can be used across the joint and angle of the 45 two diagonal ends as shown in Figure IV.

To facilitate the interchangeability of these parts each of the sections is formed on the top with the sockets 10 adapted to 50 selectively receive the securing device 11 carried at each corner of the mirror. Also the base portions are provided at the outer front corners with the slides 12 having the sockets or apertures 13 to receive the lugs 14 on the supporting slides 15 carried on 55 the bottom of the mirror frame. The positions of the slides 12 are such that they will project diagonally from the corners of the sections when extended in position that the lugs 14 may properly interlock there- 60 with whether the mirror is in the location shown in Figures V and VIII or as a connecting piece between the front corners of two spaced sections of adjacent units. This slide 12, it is to be noted does not project 65 beyond the front line of the section, while

the mirror is undercut on the back as at 16, concealing the fitting space and lying flush with the front of the sections when used as a spacer. This undercutting also serves to fit into the groove at 17 on the other end 70 of the front when the mirror is in position to close the front space between the two halves of the unit.

To best support the bottom of the mirror when in the several positions which it may 75 occupy with respect to the diagonal end of the section I preferably make use of my improved fitting illustrated in detail in Figure VIII. This member comprises the lever 18 pivoted as at 19 to the base 2 and near 80 the outer end resting on the supporting plate 20 carried by the base 2 and having the locking depressions 21 for steadyng the supporting lever in desired adjusted position. This lever is of angular formation 85 having the diagonally extending portion 22 terminating in the hooked end or retaining lip 23 adapted to overlie the front of the mirror and retain it on the support, the shape and point of pivoting of the lever 90 being such that as illustrated the end 23 will lie flat against the face of the mirror in both positions of adjustment. In this manner of supporting the mirror the slide 95 15 has a second useful function in that its inner end is constructed to, when in in- 100 wardly shifted position, interlock with the lever 18 and secure it to the bottom of the mirror and prevent accidental relative movement of the parts.

It will be noted from the foregoing taken in connection with the accompanying drawings that the several parts of my invention are all adapted for interchangeable use and that each of the several features serves for a plurality of purposes or uses according to the particular arrangement in question, the sockets 10 selectively receiving the lugs or hooks 24 of the mirror locking members 11, or the section connecting and securing members 25, the levers 18 serve to support the mirror in a plurality of positions, as do the slides 12, while the slides 15 serve interchangeably as supports or as locks for the levers 18, the mirror on account of its size 115 relative to the other parts comprising its unit and the manner of connection fills in in a number of places, while the units themselves serve to satisfactorily fill in any space in a store.

To increase the desirability of my improvement, I preferably provide suitable attachments or accessories, such as the supplemental top sections 26, while the sections themselves may be equipped on the front in 125 any desired manner, either with doors 27 as shown in Figure I, with curtains 28 or the like, while various interior fittings including shelves 29 or slide hangers 30 may 130 be made use of.

I claim:

1. A furniture unit comprising a pair of sections each having one square and one diagonally disposed end, means hingedly connecting the diagonally disposed ends for relative pivotal movement of the sections, and supplemental fastening devices for selectively securing in position the sections when folded or a supplemental section when 10 in open relation.

2. A universally adaptable furniture unit comprising a pair of similar oppositely disposed hinged sections having their adjacent ends diagonally divergent, and a mirror section for use in conjunction therewith of 15 width to close the space between the terminations of the divergent ends when the sections are in open relation and to overlie their ends when in folded relation.

3. A device of the character described comprising a pair of cabinet units hinged together at the back and having their adjacent ends diagonally divergent with respect to each other, the attachment of the hinge 25 and sections being such that the same may be brought into right angle relation, in alignment, or parallel back to back as desired, each of said sections being provided with a plurality of fastener engaging portions 30 whereby the same may be selectively employed to lock the sections in desired relative position.

4. A device of the character described comprising a pair of sections having upper 35 sockets and lower supports, and a supplemental section having overlying connections engaged in the sockets and lower slides interlocking with the supports to secure the parts in adjusted relation.

5. In a device of the character described, 40 the combination with a base, of an angular lever pivoted thereto having a retaining lip,

said lever having a supporting portion, a supporting plate for the lever, and a supplemental panel resting on the lever and 45 having a securing slide interlocking therewith to secure the parts together.

6. In an adaptable cabinet, the combination with a pair of hinged sections each having a plurality of top sockets and adjustable lower supports, of a supplemental panel member having projecting hooks for selective engagement in the sockets and adjustable slides for selective engagement with the lower supports. 50

7. A store furniture unit, comprising a pair of sections hinged at the back and having their adjacent ends forwardly diverging, said sections being foldable upon each other, the separation of the front edges of 60 the diverging ends when in open position being equal to their combined thickness when folded, and a panel of width equal to said combined thickness, and selectively interengageable means for securing the panel 65 to the sections in their varied relationships.

8. A store furniture unit, comprising a pair of cabinet sections, each of said sections having upper sockets and being provided on the under side with a sliding support member and a pivoted supporting lever, and a panel section having upper socket engaging members and bottom slides having 70 portions for selective engagement with the sliding support member and additional portions for interlocking engagement with levers. 75

In testimony whereof I have affixed my signature, in presence of two witnesses.

DAVID M. ROSENTHAL.
